RAZOR

Roy B. Bryant, Dallas, Tex.

Application July 14, 1936, Serial No. 90,582

6 Claims. (Cl. 30—72)

This invention relates to new and useful improvements in razors.

One object of the invention is to provide an improved razor particularly adapted for use with double-edged blades of the usual type but which may also be used with single edged blades.

An important object of the invention is to provide an improved razor consisting of a unitary assembly which is so arranged that the cutting blade is quickly and firmly clamped in cutting position.

Another object of the invention is to provide an improved razor of the "one piece" type in which the clamping members, for holding the blade in cutting position, are movable with relation to each other, whereby the members may be spaced a substantial distance apart to permit ready insertion or removal of the blade and also to facilitate cleaning of the razor.

20 A further object of the invention is to provide an improved "one piece" razor in which one of the clamping members is fixed and the other is movable with relation thereto, said movable member being carried by a slideable means, whereby 25 the usual screw threads or other means for actuating said member are eliminated and said member may be quickly moved into clamping position.

Another object of the invention is to provide an improved razor consisting of a unitary assembly, wherein springs, pivots, and the like are eliminated, whereby operation is simple, wear is reduced, and loss of parts eliminated. A construction designed to carry out the invention will be hereinafter described, together with other features of the invention.

The invention will be more readily understood from a reading of the following specification and by reference to the accompanying drawings, in which an example of the invention is shown, and 40 wherein:

Figure 1 is a side elevation of a razor, constructed in accordance with the invention,

Figure 2 is a front elevation of the same,

45 Figure 3 is a front elevation showing the clamping plates separated.

Figure 4 is a transverse, vertical, sectional view showing the clamping plates separated,

Figure 5 is a horizontal, cross-sectional view taken on the line 5—5 of Figure 3,

50 Figure 6 is an enlarged, detailed, sectional view showing the manner of attaching the guard plate to the rod,

Figure 7 is a plan view of a blade for the razor,

55 Figure 8 is a side elevation of a modified form of the razor,

Figure 9 is a transverse, vertical, sectional view showing the clamping plates separated,

Figure 10 is a horizontal, cross-sectional view taken on the line 10—10 of Figure 8,

Figure 11 is a plan view of a blade for use with this form of razor,

Figure 12 is an elevation of a third form of the razor,

Figure 13 is a transverse, vertical, sectional view showing the clamping plates separated, and

10 Figure 14 is a horizontal, cross-sectional view taken on the lines 14—14 of Figure 12.

In the drawings, the numeral 10 designates an elongate sleeve which is provided on its upper end with diametrically opposed horizontal arms 11. Vertical guide posts 12 extend upwardly from the outer ends of the horizontal arms 11 being at substantially a right angle thereto and in the same vertical plane with the sleeve 10. A horizontal curved clamping plate 13 has the central portion of its transverse edges secured to the upper end of the posts and forms a horizontal connection therebetween. The width of the clamping plate is greater than the diameter of the sleeve 10, as is clearly shown in Figure 1. It is preferable that the sleeve, arms, posts and clamping plate be made integral but, if desired, they may be welded or otherwise connected.

An elongate rod 14 is slidably mounted within the bore 10' of the sleeve 10 and has a length greater than the length of the sleeve, whereby its ends project beyond the ends of said sleeve. A cylindrical head 15 is formed on the lower end of the rod 14, and is enlarged, whereby the rod may be readily manipulated by grasping the head with the fingers. A collar 16 is preferably made integral with the upper end of said rod, and a guard plate 17, which is curved to conform to curvature of the clamping plate 13, rests on this collar. The guard plate is held in position on the rod 14 by a headed stud 18 which extends through a central opening 17' provided in the guard plate, and which has its lower end welded or otherwise secured within an axial opening 14' in the upper end of said rod. It is pointed out that a clearance is provided between the guard plate 17 and the head 18' of the stud 18, whereby the rod 14 and stud may be rotated without causing rotation of the guard plate (Figure 6). For maintaining alignment of the guard plate with the clamping plate 13 and also for preventing rotation of said guard plate, vertical guide slots 19 are provided in the central portion of the transverse edges of the guard plate, and said slots receive the vertical posts 12 as shown in Figure 5. The longi-

tudinal edges of the guard plate are provided with a plurality of equally spaced notches 17a to form the usual guard.

A threaded opening 13' is provided in the center of the clamping plate 13 and is in vertical alignment with the head 18' of the stud 18, whereby when the rod 14 is moved upwardly through the sleeve 10, said stud engages the opening and may be screwed thereinto. Since the posts 12 are engaged within the slots 21' of the guard plate, it is obvious that upon upward movement said plate is guided into aligned engagement with the clamping plate as shown in Figure 1.

15 A double-edged razor blade 20 is provided with a central opening 20', and a pair of opposed slots 21 are formed in the ends thereof as shown in Figure 7. The openings and slots are so positioned that when the blade overlies the guard plate 17, the opening 20' receives the head 18' of the stud 18, while the slots 21 receive the upright posts 12, whereby the blade is restrained from rotation, and upon vertical movement of the guard plate said blade is guided into aligned engagement with the clamping plate.

To place the blade in the razor, assuming that the razor is in the position shown in Figures 3 and 4, the blade is placed between the clamping and guard plates, whereby one of the posts 12 is received within one of the slots 21 provided in the ends of the blade. Each slot is of such depth that the blade may move laterally to one side of the guard plate so that the opposite end of said blade will pass within the opposite upright post 12. After the blade overlies the guard plate, it is moved into alignment therewith, whereby the opening 20' in said blade is engaged over the head 18' of the stud and the slots 21 are engaged by the posts 12 similarly to the guard plate mounting.

The rod 14 is then quickly slid upwardly within the sleeve 10 until the head 18' of the stud is in engagement with the opening 13' in the clamping plate. The rod is then rotated screwing the stud head into the clamping plate opening, and, as the blade is tightly clamped between the upper clamping plate 13 and the lower guard plate 17, it assumes the curvature of said plates and is in cutting position. To remove the blade it is only necessary to reverse the procedure.

It will be seen that as the rod 14 is readily slidable within the sleeve 10 the guard plate and blade may be quickly moved in either vertical direction, and as it is preferable that the stud head 18' be provided with coarse threads it will be seen that the rod must be turned through only a minimum number of degrees of rotation to clamp the blade in cutting position. It will be further seen that as the razor is in one piece, manipulation thereof will be facilitated and loss of parts therefrom will be eliminated. The posts 12 are of such height that the guard plate and clamping plate may be separated a substantial distance when the razor is in the open position shown in Figure 3, whereby the blades may be easily inserted or removed and the razor cleaned without difficulty.

A modified form of the invention is shown in Figures 8 to 11, wherein the arms 11' extend radially outward from the upper end of the sleeve but, instead of being diametrically opposed as hereinbefore described, extend at an acute angle to each other as shown in Figure 10. Posts 12' extend upwardly from the ends of the arms and due to the disposition of said arms lie in a plane

offset from the supporting sleeve. The clamping plate 13a is mounted between the upper ends of said posts as previously described, but in this form the posts join the clamping plate at the corners thereof formed by the transverse edges and one longitudinal edge of said plate as shown in Figures 8 and 9. The guard plate is secured to the rod 14' as has already been described, however, in this form the notches in said guide plate which engage the vertical posts 12' are provided in the corners of said plate to correspond to the position of the posts, as shown. Other structure is the same as has already been described. The further advantage of this form is the ease with which a blade, such as is shown in Figure 11, may be placed in the razor, as the posts 12' do not interfere due to their position out of the plane of the stud head and rod.

Another form of the invention is clearly illustrated in Figures 12, 13 and 14, wherein the sleeve 30 has its upper portion 30' reduced, as shown, whereby an external annular shoulder 31 is formed. One arm 32, preferably integral, extends radially from the upper end of the sleeve and an upright post 33 extends upwardly from the outer end of said arm in a vertical plane parallel to the plane of the sleeve. A curved clamping plate 34 has the center of one transverse edge fixed to the upper end of the post 33 and overlies the sleeve, its position relative to the sleeve 30 being the same as the position of the clamping plate 13 with relation to the sleeve 10 first described. The sleeve 30, arm 32, post 33 and plate 34 are preferably made integral, though they may be joined in any suitable manner.

An elongate rod 35 similar to the rod 14 already described is mounted in the same manner and likewise carries a guard plate 38 which is held in position thereon in the manner previously described. One transverse edge of said guard plate is provided with a central notch 38 which engages the vertical post 33, whereby rotation of the guard plate is prevented. A post 40 depends vertically from the opposite transverse edge of the guard plate and is parallel to and in the same vertical plane with the rod 35 and post 33. A horizontal arm 41 extends inwardly from the lower end of the post 40 and is provided on its inner end with an offset ring 42 which encircles the reduced upper portion 30' of the sleeve as shown in Figures 12 and 13 and is slidable thereon. The length of the post 40 is such that the ring 42 abuts the underside of the arm 32 when the razor is in the clamping position as shown in Figure 12. The head 39' of the stud 39 engages a threaded opening 34' in the clamping plate 34 and is screwed thereinto as previously described.

It will be seen that when the plates are separated as shown in Figure 13 the ring 42 together with the post 32 engaging the slot 38' in the guard plate serves to guide said plate as it is moved vertically.

To insert a blade in the razor, assuming that the razor is in the open position shown in Figure 13, a blade similar to that shown in Figure 7 is placed over the guard plate in such a manner that one of the slots 21 receives the post 33 and the head 39' of the stud extends through the opening 20' in the blade as hereinbefore described. The rod 35 carrying the guard plate is then moved upwardly until the head 39' of the stud engages the opening 34' at which time the rod is rotated screwing said head into the opening and clamping the blade in cutting position. The length of the rod 35 is such that the head

36 on its lower end abuts the lower end of the sleeve 30 when the razor is in the clamping position shown in Figure 12.

Thus, it will be seen that since the post 40 depends from the guard plate and is moved vertically therewith, when the razor is in the open position the post is out of the way and the blade may be easily inserted without interference therefrom. In this form the razor is also easily cleaned, and since it is unitary in structure loss of parts is eliminated. It is noted that the rod 35 is readily slidable within the sleeve 30 whereby as in the previously described forms the guard plate may be quickly moved into clamping position, and the coarse threads preferably on the stud head 39' necessitates only a minimum rotation of the rod to clamp the blade in cutting position.

What I claim and desire to secure by Letters 20 Patent, is:

1. A razor including, a stationary clamping member, a movable clamping member adapted to move into engagement with the stationary clamping member to clamp a cutting blade therebetween, a slideable rod attached to the movable member for moving the same into and out of clamping position, and threaded means on the upper end of the rod and engaging the stationary member for locking the members in their 30 clamped position.

2. A razor including, a pair of clamping members adapted to receive a cutting blade therebetween, one of said members being movable with relation to the other, a slideable rod attached to the movable member for moving the same into and out of clamping position, and threaded means carried by the rod and engaging an opening in the stationary clamping member for locking the members in their clamped position.

3. A razor including, a tubular handle, a stationary clamping member carried by the handle and spaced from the upper end thereof, an operating rod slideable in the handle, a second clamping member carried by the rod and mounted so that said rod may undergo rotation with relation thereto, and threaded means on the extreme upper end of said rod arranged to engage the stationary clamping member for locking the members together.

4. A razor including, a tubular handle, an offset arm extending upwardly from the handle, a stationary clamping member carried by the

upper end of said arm, a movable clamping member adapted to move into engagement with the stationary member to clamp a cutting blade therebetween, a rod slideable within the handle and having the movable member attached thereto, said attachment permitting the rod to undergo rotation with relation to said member, threaded means on the upper end of the rod above the movable clamping member for engaging the stationary member to clamp the same together, and 10 an offset arm having its upper end secured to the movable member and having its lower end slideable on the rod for guiding the movement of the movable member.

5. A razor including, a tubular handle, an offset arm extending upwardly from the handle, a stationary clamping member carried by the upper end of said arm, a movable clamping member adapted to move into engagement with the stationary member to clamp a cutting blade therebetween, a rod slideable within the handle and having the movable member attached thereto, said attachment permitting the rod to undergo rotation with relation to said member, threaded means on the upper end of the rod above the movable clamping member for engaging the stationary member to clamp the same together, and an offset arm having its upper end secured to the movable member and having its lower end slideable on the rod for guiding the movement of the movable member, said guide arm being opposite the supporting arm for the stationary member, whereby as the movable member is moved downwardly the guide arm moves therewith to facilitate insertion of a cutting blade 35 between the separated members.

6. A razor including, a tubular handle, a pair of arms offset out of vertical alignment with the handle and extending upwardly therefrom, a substantially rectangular clamping member supported between the upper end of the arms, a rod slideable vertically in the handle, a movable clamping member mounted on the rod so that said rod may rotate with relation thereto, said clamping being adapted to engage the stationary member to clamp a cutting blade therebetween, and threaded means on the end of the rod beyond the movable member for engaging the stationary member to lock said members in their clamped position.

ROY B. BRYANT.
